(57) **CLAIM**

We claim the ornamental design for a bottle, as shown and described.

DESCRIPTION

FIG. 1 is a perspective view of a bottle showing the new design;

FIG. 2 is a top view thereof;

FIG. 3 is a front elevation thereof;

FIG. 4 is a rear elevation thereof;

FIG. 5 is a right side elevation thereof;

FIG. 6 is a left side elevation thereof; and,

FIG. 7 is a bottom view thereof.

The broken lines in the drawings showing illustrate the portions of the bottle that form no part of the claim.
